FLASHLIGHT

William H. Doring, 44 Highview Ave.,
Old Greenwich, Conn.

Filed Dec. 19, 1963, Ser. No. 77,867

Term of patent 14 years

(Cl. D48—24)

FIG. 1

FIG. 2

FIG. 3

FIG. 4

FIG. 5

FIGURE 1 is a top plan view of a flashlight embodying my design;

FIGURE 2 is a side elevational view thereof;

FIGURE 3 is a partial sectional view taken along the line 3—3 in FIGURE 2, showing the inner configuration of the lens ring;

FIGURE 4 is a front view of the flashlight; and

FIGURE 5 is a rear view thereof.

I claim:

The ornamental design for a flashlight, substantially as shown and described.
